SPRAY GUN WITH REMOVABLE DISCHARGE TUBE

William H. Rose, Jersey City, N. J., assignor to
Stanco Incorporated, a corporation of Delaware

Application October 16, 1935, Serial No. 45,276

6 Claims. (Cl. 299—89)

This invention relates to improvements in spray guns, particularly of the hand operated, continuous type adapted for various purposes, such as the spraying of insecticidal solutions.

- 5 An object of the invention is to provide a simplified construction, capable of efficient operation throughout long periods of service, in which the discharge tube is mounted for ready removal and cleaning.
- 10 A further object is to provide a device in which the discharge of non-vaporized liquid is prevented at all inclinations in which the spray gun is likely to be used.

A further object is to improve the construction 15 of the mixing chamber and discharge opening in devices of this kind and to locate these parts in a novel and advantageous position on the upper part of the barrel of the spray gun.

The foregoing and other objects of the invention will be clear from the following description read in connection with the accompanying drawing, in which

Fig. 1 is a vertical section through a preferred type of spray gun;

25 Fig. 2 is a front elevation of the same;

Fig. 3 is an enlarged detail sectional view of a modified type of discharge opening;

Fig. 3a is a phantom front view, in enlarged detail of the modified type of discharge opening 30 shown in Fig. 3.

Fig. 4 is a detail view of a discharge tube having means for facilitating removal;

Fig. 5 is a detail view of a discharge tube having centering means; and

35 Fig. 6 is a plan view taken at II—II of Fig. 5.

Referring first to Figs. 1 and 2, reference numeral 1 denotes a liquid reservoir and 2 a spray gun barrel, both of which may be of the conventional type. The invention is particularly 40 adapted for continuous sprayers and in the form shown there is the usual check valve 3 in a partition 4. The plunger 5, the end cap 6, closing the front (filling) opening, and end cap 7, closing the plunger chamber, may be of any desired 45 form. Preferably a gasket 8 is provided under cap 6 to prevent the escape of fluid and to make the construction air tight.

An important novel feature of the invention is 50 the discharge tube 9, preferably straight, arranged in a sleeve 10 which is fastened by soldering or otherwise to the upper part of barrel 2. The sleeve is closed by a cap 11 which is secured to the sleeve by screw threads, a friction 55 fit, or the like, and is adapted for easy removal.

This construction provides a sort of turret on the top of the gun barrel.

The discharge tube has its lower end resting 5 on the bottom of the liquid reservoir 1 in the form shown, although it may be supported clear of the bottom, as later described. There is sufficient opening between the edge of the tube bottom and the curve of the reservoir to permit the entry of liquid into the tube, to be drawn up through it when air is forced past the outlet 10 of the tube on the instroke of the plunger and when the built-up pressure is discharged on the outstroke. The ball valve 3 is arranged for this type of continuous spraying. The tube has a limited freedom of motion in the sleeve and can 15 be readily lifted out for cleaning.

There is in the cap 11 a small opening 12 through which the atomized liquid is discharged. The space 13 between the top of the cap and the upper end of tube 9 serves as a mixing chamber 20 in which the air and the liquid are commingled for discharge as a spray through opening 12.

Referring to Fig. 3, a modified form of the discharge fitting is shown. This comprises a casting or other suitable member 14 in which there 25 is a mixing chamber 15 of inverted funnel form having an outlet passage 16. The passage terminates with edges flaring outwardly as at 17 to form a funnel shaped mouth.

Although it is readily possible to remove discharge tube 9 shown in Fig. 1 simply by unscrewing cap 11 and lifting the tube out with the fingers, it is a little more convenient to attach a device such as the small handle 18 shown in 30 Fig. 4.

The limited play of the tube in sleeve 10 does 35 no harm, but if positive centering of the tube is desired, this may be accomplished by providing one or more arms 19, Fig. 5, attached near the upper end of the tube and of such length and 40 distance from the top as to support the tube on the sleeve and prevent it from slipping sideways toward the sleeve.

Spray devices sometimes become clogged after 45 extended use, due to the presence of solid or gummy material which gets into the reservoir. In the ordinary type of spray gun it is very difficult, if not impossible, to clean the discharge tube and restore the spray gun to its normal 50 functioning. In the present device this cleaning is accomplished very easily by taking out the tube as described and running a straw or small wire through it. It is preferred to use a straight tube but the cleaning can be accomplished 55

readily enough even though curved tubes are provided.

A further defect of certain types of spray gun is their tendency to discharge solid streams of liquid, instead of atomized liquid if the spray gun is held at a sharp angle up or down. This is due to the fact that the discharge opening is placed low on the barrel, usually in the end. In the present invention it will be seen that the discharge opening is placed on the top of the barrel, so that even though the spray gun is held at sharp angles, solid streams of liquid will not be discharged.

Also I have found that it is not only convenient to have the spray discharge from a mixing chamber above the barrel instead of at the end, as in the common type of sprayer, but also results in a considerable simplification. The mixing chamber (13, 15) provided in the turret-like construction (10, 11) avoids the necessity for providing a plate having a number of air distributing openings around a central discharge tube. The reservoir may be filled through the mixing chamber, but it is preferred to provide a separate filling opening, such as the end cap 6.

The construction described is for illustration only and various changes and alternative arrangements may be made within the scope of the appended claims, in which it is my intention to claim all novelty inherent in the invention as broadly as the prior art permits.

I claim:

1. A spray gun including a pump barrel, a reservoir carried thereby and a discharge assembly comprising an annular sleeve secured in an opening in a side wall of the pump barrel, a discharge tube freely positioned therein and removable through the sleeve, said tube extending through the barrel and continuing into closely

spaced relation to the bottom of the reservoir, and a removable cap for the sleeve free of said tube and forming with said sleeve a chamber surrounding the tube end, said cap having a discharge port communicating with the chamber. 5

2. Apparatus according to claim 1, in which the tube has a lifting device attached thereto and extending into the chamber surrounding the tube end.

3. Apparatus according to claim 1, in which 10 the discharge tube is straight.

4. A spray gun according to claim 1, in which the discharge tube is positioned within the sleeve, with its upper end in the chamber formed by the cap and sleeve, by means of radial arms on the 15 tube disposed in diametrically opposed pairs spaced circumferentially and longitudinally of the tube, of which one pair freely engages the upper end of the sleeve and another freely engages the inner wall of said sleeve adjacent its 20 lower end.

5. A spray gun according to claim 1, in which the annular sleeve is disposed in an opening in the top of the pump barrel, protruding therefrom, and which with the cap therefor forms a 25 turret-like discharge member for the gun.

6. A spray gun including a pump barrel, a reservoir, a discharge assembly extending through a side wall of said pump barrel and a means for replenishing said reservoir comprising a pressure chamber in the pump barrel, communicating with a nozzle in the discharge assembly and with the reservoir, opening outwardly through one end of said barrel, and a removable closure for said chamber which, when 35 the closure is removed, provides a passageway through which the reservoir may be filled. 30
